UNITED STATES PATENT OFFICE

166,422

IDENTIFICATION MEDALLION

William Stayback, Riveredge, N. J.

Application April 10, 1951, Serial No. 14,776

Term of patent 3½ years

(Cl. D29—19)

To all whom it may concern:

Be it known that I, William Stayback, a citizen of the United States, residing at Riveredge, State of New Jersey, have invented a new, original, and ornamental Design for an Identification Medallion, of which the following is a specification, reference being had to the accompanying drawing, forming a part hereof and wherein:

Fig. 1 is a front elevational view of an identification medallion, showing my new design;

Fig. 2 is a rear elevational view of the identification medallion of Fig. 1; and

Fig. 3 is a vertical sectional view taken along the line 3—3 of Fig. 2.

I claim:

The ornamental design for an identification medallion, as shown.

WILLIAM STAYBACK.
